UNITED STATES PATENT OFFICE.

JOHN W. WATTS, OF MONTGOMERY, ALABAMA.

THILL-HOLDER FOR HARNESS.

SPECIFICATION forming part of Letters Patent No. 313,266, dated March 3, 1885.

Application filed May 17, 1884. (No model.)

To all whom it may concern:

Be it known that I, JOHN W. WATTS, of 5
Montgomery, in the county of Montgomery
and State of Alabama, have invented certain
new and useful Improvements in Thill-Holders
for Harnesses, of which the following is a full,
clear, and exact description.

Reference is to be had to the accompanying
drawings, forming part of this specification, in
10 which similar letters of reference indicate cor-
responding parts in all the figures.

Figure 1 is a side elevation of the back-pad
and skirt of a harness having my improved
thill-holder applied thereto. Fig. 2 is an edge
15 view of the thill-holder as it appears when
looped for holding the thill; and Fig. 3 is a
front elevation of the holder unlooped.

This invention has for its object to facilitate
the work of hitching horses to one-horse vehicles;
20 and the invention consists in providing
the harness with thill-holding straps instead
of loops, the straps being adapted to be wrapped
around the thills and secured by a snap-hook
or buckle and ring, thus avoiding the necessity
25 of sliding the thills through loops, as is now
the common practice.

Referring to the drawings, A represents the
back-pad or saddle of the harness, and B re-
presents the skirt of a harness, which said parts
30 may be of the ordinary or of any approved con-
struction. In this instance the skirt and thill
strap or holder C are made in one piece; but
the latter may be made separate and buckled
35 or otherwise secured to the skirt, if desired.
The thill-holder C is a plain strap of suitable
length to be wrapped around the thill, and pro-
vided at its outer end with the ring D, which
is adapted to be held by the snap-hook E, se-
40 cured to the strap or holder C the proper dis-
tance from its lower or free end, as will be un-
derstood from the drawings.

The snap-hook is made adjustable on the strap
B by means of a pivoted tongue, F, (shown in

dotted lines, Fig. 1,) adapted to engage one
of a series of holes, a, in said strap when the 45
snap-hook is slid to its proper position.

In use, the horse to be hitched to the vehicle
will simply be placed in the thills, and the
thills raised and the thill-holders C passed un-
der and around the thills, and the ring D placed 50
in the hook E. In this manner the trouble of
slipping the thills through thill-loops is avoid-
ed; and the thill-holder is cheap, practical,
and convenient, and can be applied to all kinds
of harness.

I prefer to make the thill-holder C an ex-
tension of the skirt B of the harness; but for
harness already in use the thill-holder C may
be made of a separate strap adapted to be
buckled to the skirt in place of the ordinary 60
thill-loops.

I am aware that a halter-strap has been pro-
vided with a sliding snap-hook for engaging
a ring or loop on the end of the strap; also,
that a saddle has been provided with a strap, 65
around which metallic clasps were passed.
To these clasps a plate was secured, the plate
being bent to form a loop, and being provided
with a spring carrying a pin to hold it in po-
sition on the strap; and I do not claim such 70
constructions as of my invention.

Having thus described my invention, I claim
as new and desire to secure by Letters Patent—

The combination, with the saddle A, of
straps B, secured thereto and provided with 75
rings D at their lower ends, apertures a, and
a sliding snap-hook constructed to engage said
apertures, whereby the strap may be wrapped
around the thill to form a loop, C, after the
animal has been placed within a thill, substan- 80
tially as set forth.

JNO. W. WATTS.
